UNITED STATES PATENT OFFICE.

JOHN HESKET WRIGHT, OF COLUMBUS, OHIO.

DESIGN FOR AN INCANDESCENT-ELECTRIC-LAMP SHADE.

SPECIFICATION forming part of Design No. 30,787, dated May 16, 1899.

Application filed March 20, 1899. Serial No. 709,860. Term of patent 7 years.

To all whom it may concern:

Be it known that I, JOHN HESKET WRIGHT, a citizen of the United States, residing at Columbus, in the county of Franklin and State of Ohio, have invented and produced a new and original Design for Shades for Incandescent Electric Lights; and I do hereby declare the following to be a full, clear, and exact description of the invention, such as will enable others skilled in the art to which it appertains to make and use the same.

In the accompanying drawings, in which I have illustrated an embodiment of my design, Figure 1 is a top plan view, and Fig. 2 is a 15 central vertical sectional view.

As shown, my shade is, generally speaking,

of the form of a hollow truncated pyramid—that is, with flat sides 1, that taper toward each other at the top; but at the top there is a subtending wall 2, provided with a circular ²⁰ opening 3, while the base of the shade is entirely open and free.

I claim and desire to secure by Letters Patent—

The design for an incandescent-electric- ²⁵ lamp shade, as shown and described.

In testimony whereof I affix my signature in presence of two witnesses.

JOHN HESKET WRIGHT.

Witnesses:

GEORGE W. ALFRED,

GEORGE M. FINCKEL.
